[57] CLAIM

The ornamented design for an electronic tuner for musical instruments, as shown and described.

DESCRIPTION

FIG. 1 is a perspective view of an electronic tuner for musical instruments showing my new design;
FIG. 2 is a front elevational view thereof;
FIG. 3 is a right side elevational view thereof;
FIG. 4 is a left side elevational view thereof;
FIG. 5 is a top plan view thereof; and,
FIG. 6 is a bottom plan view thereof.
The rear elevational view is unornamented and forms no part of the claimed design.
